CANOPY FOR BROODER STOVES

Anson J. Meeks and Louie W. Meeks, Hillsdale,
Mich.

Application December 5, 1936, Serial No. 114,476

3 Claims. (Cl. 119—32)

This invention relates to a canopy for brooder stoves and has for an object to provide an auxiliary adjustable canopy which will properly diffuse the heat of a stove.

5 The conical canopy of a brooder does not properly diffuse heat because the heated air under the canopy moves to the outer edge of the canopy where it immediately begins to rise. Chicks under such a canopy have only a space of from 10 six to eight inches where the heat is such that it may be called "hovering". That space is directly under and just outside of the edge of the canopy. Further under the canopy it is too hot and further out it is too cold. Thus chicks, in 15 order to secure the desired warmth, pile up and trample one another.

Another disadvantage of the conventional conical canopy is that too much light exists, with the resultant sensation to the chick that it is not being "hovered", and this causes uneasiness 20 and bunching of chicks.

With the above disadvantages in view the present invention provides a flat canopy in the nature of a cloth awning, constructed in sections, 25 which sections extend outside from the conical stove canopy several inches, underneath which awning the heat is properly diffused over a space sufficiently large for a greatly increased number of chicks, and throughout this space the chicks are more perfectly hovered and the tendency to trample, crowd and bunch is reduced to a 30 minimum.

With the above and other objects in view the invention consists of certain novel details of construction and combinations of parts hereinafter 35 fully described and claimed, it being understood that various modifications may be resorted to within the scope of the appended claims without departing from the spirit or sacrificing any of the 40 advantages of the invention.

In the accompanying drawings forming part of this specification,

Figure 1 is a plan view of a brooder equipped 45 with a canopy constructed in accordance with the invention, parts being broken away and parts removed.

Figure 2 is a longitudinal sectional view through the brooder and canopy taken on the line 2—2 of Figure 1.

50 Figure 3 is an enlarged front elevation of one of the lower sections of the canopy with adjoining upper sections lapped thereover and showing the guard frame to prevent chicks from hopping up on top of the canopy.

55 Figure 4 is an end elevation of one of the lower

sections showing the adjustable legs upon which the canopy is supported.

Figure 5 is a detail sectional view taken on the line 5—5 of Figure 4.

Figure 6 is a detail sectional view taken on the line 6—6 of Figure 4.

Figure 7 is a plan view of one of the blankets and its hang.

Referring now to the drawings in which like characters of reference designate similar parts in the various views, 10 designates the stove and 11 the conical canopy of a conventional brooder. The canopy comprising the subject matter of this invention is formed in sections, certain of the sections 12 being provided with front legs 13 and 15 rear legs 14 and the remainder of the sections 15 being supported upon and overlapping the legged sections. To adjust the sections for various sizes of stove canopies 11, it is only necessary to let the upper sections 15 overlap more or less the lower 20 or supporting sections 12. The sections are each formed of wire netting 16 stretched on a wire frame 17 the sides of which are reinforced with sheet metal strips 18. The strips of the lower supporting sections 12 are provided with sockets 25 19 which slidably receive respective legs 13 and 14 that are longitudinally slotted as shown at 21 to receive clamp bolts 22 passed through eyes 23 on the wire frame and through the sockets to 30 adjustably secure the supporting sections 12 to the legs so that the height of the sections above 35 the ground may be varied to suit various conditions of service.

The sockets 19 are provided with eyes 24 to receive the legs of inverted U-shaped frames 25 35 over which wire netting 26 is stretched. Adjoining frames 25 are connected together by hooks 27. The covered frames 25 form a guard rail on top of the canopy to prevent the chicks from jumping up on to the canopy.

40 All of the sections are provided with individual cloth blankets 28, corresponding to the shape of the sections as shown in Figure 7, and each blanket is provided with a drop or hang 29. The blankets are laid on the sections to overlap the 45 brooder canopy 11 and the hang may be looped back upon itself as much as is desired to vary the size of the opening between the hang and the ground.

From the above description it is thought that 50 the construction and operation of the invention will be fully understood without further explanation.

What is claimed is:

1. A canopy for brooder stoves comprising 55

- upper and lower substantially horizontal screen wire sections disposed in overlapping relationship adjacent to the lower edge of a conventional brooder stove canopy and forming a hover extending several inches therebeyond, supporting legs for certain of the sections, and blankets for covering the sections, each blanket having a hang adapted to hang down over the outer end of the respective section.
- 10 2. A canopy for brooder stoves comprising wire screen sections each having a marginal wire frame, legs on certain of the sections, others of the sections being adapted to be superposed upon and to overlap the legged sections, and a respective blanket supported by each section, the blanket having a hang, said sections and said blankets being adapted to be mounted in surrounding relationship to the conventional canopy of a brooder stove and provide a cover extending several inches beyond the edge of said brooder stove canopy.

3. A canopy for brooder stoves comprising screen wire sections provided with marginal supporting frames, certain of the sections being provided with front legs and with rear legs, means for adjusting the length of said legs, others of the sections being adapted to be superposed upon and overlap the legged sections, adjustment of the sections to fit various sizes of stove canopies being made by varying the lap of the superposed sections upon the legged sections, sockets 10 on said front legs, guard frames formed of screen wire, certain of the guard frames having portions received in said sockets, others of the guard frames being detachably secured to the first named frames, said guard frame sections 15 preventing chicks from hopping up on to the canopy sections, and a respective blanket for each canopy section having a hang adapted to hang down along said front legs.
